UNITED STATES PATENT OFFICE.

FRANZ GOGEL, OF KEHL, GERMANY.

ROLLER-STAMP.

No. 872,337.

Specification of Letters Patent.

Patented Dec. 3, 1907.

Application filed April 18, 1907. Serial No. 368,960.

To all whom it may concern:

Be it known that I, FRANZ GOGEL, a subject of the Emperor of Germany, residing at Kehl-on-the-Rhine, Germany, have invented 5 certain new and useful Improvements in Roller-Stamp, of which the following is a specification.

This invention relates to roller stamps with interchangeable type in which the ordinary letters are arranged in special sector shaped type cases, which with the type as a whole are fitted around a roller core, so that they as a whole form a roller shaped stamp.

One form of my invention is shown in the 15 accompanying drawings, in which

Figure 1 shows the use of such a stamp on a bill; Fig. 2 is a side view of the stamp; Fig. 3 is a section on the line A—B of Fig. 2; and Figs. 4 and 5 are details of the roller stamp.

20 The apparatus consists of a roller core *b* through which passes a hollow axle *a*. Against the outer cylindrical surface of the roller are fitted the sector shaped type cases *c* arranged radially one against the other. 25 The type cases are provided with a set screw *e* on the narrow side piece *c¹* which is easily accessible from the outside, and on which, to facilitate corrections, is pasted a copy *c²* of the matter. This set screw serves to hold in 30 the known manner the inserted lettering *d*, and to facilitate its exchange. In order to facilitate the even laying of the letters on the one hand and their correct placing on the other a rib *f* (Fig. 5) is arranged along one 35 side of the letter cases, against which the type notches rest. In this way the inverted insertion of letters is prevented so that the filling of the matrices may be effected by an inexperienced person. The space remaining 40 in the letter cases is filled up with a spacing piece. Ordinary book printing letters are used.

The radially shaped letter cases lie quite close to one another and are arranged in 45 thickness according to the space between the lines. The latter can however be formed by wedge shaped spacing pieces *g*. If lines are to be left free empty cases or wedges of the same shape are arranged in the space as also 50 where the type does not fill up the roller. The type cases and the wedges may be made of wood. The letter cases can be inserted as desired and can therefore be kept ready for use with projecting characters.

The letter cases arranged around the roller 55 core are held together by a fixed ring *h* and a loose band ring *h¹* and secured to a roller which may be moved by means of a spindle *k* provided at the ends with a removable handle *k¹* (Fig. 1). The side of the roller provided with the printed label referred to is closed from outside by a pressing disk *i* and a nut *l*, with a rubber ring *q* arranged between the letter cases *c* and the pressing disk. At the other side is the fixed disk *r*.

60 The method of operation which is shown by Fig. 1 is as follows:—After inking the type the roller is placed on the paper so that the first name or sentence comes between the first and second lines of the previously printed water lines, then the roller is moved parallel to the sides, in the direction of the arrow in Fig. 1 and a print of all the sentence is then made on the paper. To insert the characters it is only necessary to take off the pressure disk and the rubber ring. The whole 65 list of characters is then before the operator and the letter cases are loose, so that they can be removed where required and replaced in other positions. The gaps are closed by 70 pressing the other letter cases together, leaving the further necessary spaces. The letter cases can also be removed from the roller to 75 be used separately, for example, to print the characters on receipt forms, delivery notes 80 and the like.

85 What I claim as my invention and desire to secure by Letters Patent is:—

1. In a roller stamp the combination of a cylindrical core *b*, axle *a*, end disk *r*, wedge 90 shaped type cases *c* arranged radially on the core, a fixed ring *h* and a loose ring *h¹* securing the cases, and a pressing disk *i* and nut *l* securing them at the end, as herein described.

95 2. In a roller stamp the combination of a cylindrical core *b*, axle *a*, end disk *r*, wedge shaped type cases *c* arranged radially on the core, side piece *c¹*, adjusting set screws *e* and means for securing the cases at their ends 100 and circumference.

In witness whereof I have hereunto set my hand in the presence of two witnesses.

FRANZ GOGEL.
